UNITED STATES PATENT OFFICE.

BERNIS M. SHIPLEY, OF DAYTON, OHIO, ASSIGNOR TO THE NATIONAL CASH REGISTER COMPANY, OF DAYTON, OHIO, A CORPORATION OF MARYLAND.

DESIGN FOR A CASH-REGISTER CABINET.

Application filed February 4, 1928. Serial No. 25,205. Term of patent 14 years.

To all whom it may concern:

Be it known that I, BERNIS M. SHIPLEY, a citizen of the United States, residing at Dayton, in the county of Montgomery and State of Ohio, have invented a new, original, and ornamental Design for Cash-Register Cabinets, of which the following is a specification, reference being had to the accompanying drawings, forming part thereof, in which—

Fig. 1 is a perspective view showing the front, right side and top of a cash register cabinet showing my new design.

Fig. 2 is a perspective view showing the rear left side and top of the cash register cabinet.

Fig. 3 is a view in side elevation of the cash register cabinet shown in Figs. 1 and 2.

What is claimed is:

The ornamental design for a cash register cabinet as shown.

In testimony whereof I affix my signature

BERNIS M. SHIPLEY.
